ELECTRIC BICYCLE LANTERN

Eric T. New, Forest Hills, N. Y.

Application April 13, 1956, Serial No. 41,061

Term of patent 7 years

(Cl. D48—24)

Fig. 1.

Fig. 2.

Fig. 1 is a top perspective view of an electric bicycle lantern showing my new design; and

Fig. 2 is a bottom perspective view thereof showing the side opposite that shown in Fig. 1.

I claim:

The ornamental design for an electric bicycle lantern as shown.
